FLY TRAP

Wilber W. Randle, 3515 Sheffield Ave.,
Los Angeles, Calif. 90032

Filed Nov. 8, 1965, Ser. No. 88,045

Term of patent 14 years

(Cl. D31—3)

FIG. 1.

FIG. 2.

FIG. 4.

FIG. 3.

FIG. 5.

FIG. 6.

FIG. 1 is a side elevational view of a fly trap showing my new design;

FIG. 2 is a top view of FIG. 1;

FIG. 3 is a bottom view of FIG. 1;

FIG. 4 is a sectional view taken in the plane indicated by line 4—4 of FIG. 1;

FIG. 5 is a sectional view taken in the plane indicated by line 5—5 of FIG. 1;

FIG. 6 is a fragmentary sectional view taken in the plane indicated by line 6—6 of FIG. 1.

I claim:

The ornamental design for a fly trap, as shown.
